DESIGN FOR A DIE HEAD

Carl H. Ingwer and Clyde E. Wright,
Elyria, Ohio

Application December 12, 1938, Serial No. 81,712

Term of patent 14 years

To all whom it may concern:

Be it known that we, Carl H. Ingwer and Clyde E. Wright, residents of Elyria, in the county of Lorain and State of Ohio, have invented a new, original, and ornamental Design for a Die Head, of which the following is a specification, reference being had to the accompanying drawing, forming a part thereof.

Fig. 1 is a front view of a die head embodying our design; and

Fig. 2 is a side view thereof.

We claim:

The ornamental design for a die head, substantially as shown and described.

CARL H. INGWER.
CLYDE E. WRIGHT.
